DEVICE FOR COLLATING TISSUE PAPER
GARMENT PATTERNS FROM STACKSAugust G. Luisada, New York, N. Y., assignor to
Advance Pattern Co., Inc., New York, N. Y., a
corporation of New York

Application June 19, 1950, Serial No. 169,045

1 Claim. (Cl. 270—58)

1

This invention relates to a machine for picking tissue paper garment patterns one by one from stacks of about 1,000 patterns, collating one each of the patterns required to make one garment and folding such an assembled group.

The principal object of the invention is to provide a novel and relatively simple machine for picking single sheets, and only single sheets, of tissue paper from each of a number of stacks without missing a sheet, collating this number of tissue paper sheets of various sizes and shapes into a group, in a simple and effective way, and making a first folding operation of the assembled group.

Once this operation is accomplished, the difficulties which were heretofore encountered, of handling tissue paper sheets of endless variable sizes and shapes, are overcome, because a fold of a standard size and more substantial weight can be folded again on presently known folding machines, to the size of the envelope in which it may be placed by known mechanical means.

Further objects are to provide a machine which can be easily loaded despite the diversity of the patterns and in which no delicate adjustments are required to change over from one to another set of patterns which can, therefore, be run by unspecialized hands, and which produces faultless assemblies.

In the drawings:

Fig. 1 is a diagrammatic sectional view of the machine.

Fig. 2 is an end view of the collating mechanism as viewed from the right of Fig. 1, along line 2—2.

Fig. 3 is a top plan view of the pattern carriage plates.

Fig. 4 is a fragmentary view of the collating members, drawn to an enlarged scale, parts being broken away for clarity.

Fig. 4a is a view of a detail, partly shown in Fig. 4.

Fig. 5 is a top plan view of the picking mechanism, the top plate being removed to show the interior.

Fig. 6 is a side view of the picking mechanism.

Fig. 6a is a side view of the front holding member, partly shown in Fig. 6, removed from the assembly to show the shape more clearly.

Fig. 6b is a side view of the moving member removed from the assembly to show the shape more clearly; spring and cam collaborating with the moving member are also shown.

Fig. 6c is a side view of the rear holding member removed from the assembly to show the shape more clearly.

2

Fig. 6d is a fragmentary view of a paper stack as shown in Fig. 6, showing the holding and moving members in the position of separating the top sheet of a pattern stack.

5 Fig. 7 is a partial sectional view of the slide and roller wings as indicated in Fig. 8 by the broken line 7—7.

Fig. 8 is a sectional view of the rolling and folding device.

10 Fig. 9 is a sectional view similar to Fig. 8, but showing a modification of the rolling and folding device.

The machine as shown in Figs. 1, 2, and 4, consists of a frame 1 which supports the shafts 3

15 and 4, which in turn support the sprockets 5, 6, 7, and 8, and the chains 10. Shaft 3 may be driven by the motor 11. Rods 12 connecting the chains are rotatably assembled to the chains by the eyes 13 (Fig. 4) and are spaced at equal 20 distances in two symmetrical groups of seven each so that the centrifugal force of one group is balanced by the force of the other group. Under this chain assembly, a group of sixteen cams 14 extend parallelly along the chains and 25 are fastened to the frame at both ends.

Under the cams 14, one of two pattern carriages 2 may be removably inserted into the frame. This arrangement allows one pattern carriage to be reloaded while the pattern stacks 28 (Figs. 4 and 5) of the other carriage are being picked in the machine. The pattern carriage supports six plates 21—26 in spaced apart relation, staggered to the rear. On the five lower plates, pattern stacks may be disposed. The pattern stacks 28 (Figs. 4, 5 and 6) are disposed in such a way on the plates that preferably a corner of each stack covers the portion 17 on each plate, and the portion 17 forms a definite pattern as shown in Fig. 3. These portions are marked clearly on the plates to facilitate reloading the plates when removed from the machine. The pattern stacks are placed lengthwise on these plates so that the center of gravity of each pattern is roughly in line with the respective portion 17. Preferably the longest patterns will be disposed on the longest or lowest plate, and successively shorter patterns on the successively upper plates. Each of the plates 21 to 26 has slots 27 over the portion 17 of the lower plates; and their forward ends are bent down along the lines 19 to lie in a single plane parallel to the cams 14, leaving a mouth 29 between each pair of adjacent plates.

The general path of the patterns through the machine is the following: The pattern stacks 28 45 are disposed over the portions 17 on the plates

50

55

21 to 25. Picking mechanisms 32 (Figs. 5 and 6) are placed and clamped adjacent each stack 28 to separate the top sheet of pattern from the rest of the stack and to hold the stack in place. Carrying members 33 are carried by the rods 12 and lowered on each of the stacks through the slots 27 on the portions 17 to slide the top pattern down each stack to the supporting plate and through the mouth 29 between the plates whereby the patterns are collated. The collated assembly of patterns is carried further by the group of carrying members 33 on to the conveyor 37, moving in the same direction as the carrying members. The conveyor 38 overlies and cooperates with conveyor 37. The assemblies are then introduced by said conveyors into the roll-forming mechanism 40 which rolls up each assembly to form a roll, flattens the roll to form a flat fold which is then deposited on the table 42 from which it may be fed to a conventional folding machine.

The picking mechanism 32 consists of a base plate 51 (Figs. 5, 6, 6a, 6b, 6c) which has a cut-out 52. This base plate is provided with a clamping arrangement (not shown) to be secured to the plates 21 to 25, on which it rests, but to be easily shiftable to another spot on the plate when a pattern stack of a different shape is to be picked, and such shifting is required. The base plate 51 and the body 54 are connected by two pairs of cross links 53 which support the body 54 in a position parallel to the base plate 51, allowing said body to be raised to the height of the stack to be picked and to be lowered into the cut-out 52 to pick the last sheets of the stack. This body supports on guides 56 (Figs. 5 and 6) a reciprocating member 55, having two pairs of pins or rollers 57. To the rear of the body 54 are pivoted a pair of arms 58 connected at their front end to form the front holding member 59; another pair of arms connected at their front ends forming the rear holding member 59 (Fig. 6a). The arms of the moving member 60 (Fig. 6b) are pivoted to the upper pins 57 and movable with the reciprocating member 55. Their extension 61 is placed to engage the cam 62 and the spring 63. The reciprocating member can be moved by the flexible shaft 64 which connects it to two solenoids or other motive device (not shown), one pulling, one pushing, located at the rear of each plate 21-25.

When the machine is loaded, the body 54 of the picking mechanism is raised manually and one of the holding members is placed to rest upon the new pattern stack so that the rear holding members 59 are in a position adjacent a border of the stack 28. They are in raised position when the pins 57 are at the rear end of their stroke as indicated by the broken line 65 of Figs. 6a-6c. The arms of the front and rear holding members are shaped as cams, having straight portions, keeping them in position and angular cam surfaces 66 and 67 to raise or lower them when the pins 57 pass along these portions. The tip of the moving member 60 is provided with a cushion 68 of elastomer which has a high coefficient of friction against paper. Preferably, the pressure exerted against the top sheet should be about 1 oz. per square inch of contact surface. The holding members 58 and 59 may be provided with similar cushions 68. Upon reaching the rear end of its stroke, the extension 61 of the member 60 bypasses the spring 63 on which it was sliding, and the cushion 68 of the member 60 is allowed to drop onto the top sheet. Upon forward move-

ment of the reciprocating member 55 the moving member will cause the top pattern to crimp against the front holding member 59 (see Fig. 6d) which is supporting the weight of the body 54 on the stack until a sufficient space is freed by the top sheet, at which time the pins 57 reach the cam surface 67 of the rear holding member 59 causing it to be lowered on the second sheet to support part of the weight of the body 54 on the second sheet whereupon the pins 57 reach the cam surface 66 of the front holding member 58, raising it and freeing the top sheet as extension 61 hits the cam 62 deflecting the spring 63 in passing, raising the member 60 from the top sheet which is now ready to be removed by the carrying member 33 to be collated, while the rear holding member holds the second sheet in position to prevent the pack from being disturbed by the impact of the carrying member 33. An electric contact (not shown) causes the pull solenoid to be energized to move the reciprocating member to the rear at the time when a group of carrying members has passed. The extension 61 is sliding from the straight portion of the cam to the spring which supports the tip of the moving member to keep it clear of the top sheet while the front member is lowered, and the rear member raised whereupon the moving member is dropped on the top sheet when 61 passes the end of the spring 63. The push solenoids may be energized by another contact on the chain or upon the pull solenoid reaching the end of its stroke.

The collating mechanism (Fig. 4) includes carrying members 33, two groups of which are supported by the two groups of rods 12. Each of these groups comprises seven rods, the first and last of each group serving for auxiliary purposes while the central five rods support the carrying members which do the collating by carrying each one pattern from the top of each stack, reaching each through one slot 27 to touch one portion 17 to carry one pattern through the mouth 29 to form the assembly on the plane formed by the forward ends of the plates 21 to 25. These central five rods of each group support the carrying members corresponding to the five plates and are arranged in the same general pattern as the portions 17 are arranged on the five sheets, an example of such a pattern being shown on Fig. 3, in which 16 stacks are shown to be arranged on five plates, in which the distances between any two adjacent stacks are equal. This distance may be chosen to be superior to the average width of all the patterns to be handled by the machine. The lowest plate 21 has three areas 17 and three carrying members are to be carried by the first rod, arranged to align with said three areas. The second plate 22 has four areas 17 to which the four carrying members on the second rod are aligned, etc. Each carrying member of one group has a path for itself, not occupied by any other carrying member and a cam 14 to extend along said path to guide it to touch the respective area 17 to take and carry the top sheet of said pattern stack after it has been separated from the second sheet and the second sheet is positively prevented from being carried with it by the holding member 59 of the respective picking mechanism.

Each of the five rods 12 supporting carrying members 33 is linked to the preceding rod 12 by a link 72 which has a slot 73 engaged by the preceding rod, to prevent it from turning freely. To each of said rods, supports 75 are fastened to support the carrying members 33, by the pins 76

in its own path adjacent its cam 14. The pin 77 on the support 75 supports the hook member 78, having a pin 79. This pin is arranged to slide along the top of the cam 14 and to engage the cam groove 80 upon reaching its entrance 81. The hook member 78 has a hook 83 disposed to engage the succeeding rod 12 when the pin 79 is moved upward by the end of the groove 80 at 84 to slide on the top of the cam 14. The movement of the two preceding rods 12 around sprockets 7, 8, will cause the hook in this position, shown in broken lines 83' to be engaged by a rod 12 when the preceding rods 12 have reached the sprocket 3, and then to be lifted from the cam. Upon reaching the straight portion of travel from sprockets 7, 8 to sprockets 5, 6, the hook will disengage but rest by its weight on rod 12, to engage it again upon reaching sprockets 5, 6 to be unlocked after passing these to allow the pin 79 to slide on cam 14, and engage groove 80 at 81. The hook member 78 has also a restraining loop 86 to engage the cam guide 87 secured to the carrying member 33. The carrying member has a tip 90 made preferably from elastomeric material which has an extension in a forward direction and one to its rear which has the purposes of providing high friction, cushioning the shock upon reaching the top sheet of the stack 28, decreasing the relative pressure on the paper by increasing the supporting area, and preventing the loss of the sheet when sliding down the stack by producing traction on the sheet against the edge of the stack until the forwardly directed extension takes over by a heel and toe action by producing traction on the sheet, reaching the plate 22 as shown in broken lines 33'' and 90''. The carrying member is urged by the coil spring 93 to produce pressure on the carried sheet, the other end of which spring may be fastened to the preceding rod 12 by the arm 94. When the pin 79 is on top of the cam 14, the member 33 is lifted by the loop 86 and the guide 87 away from the bent extensions of the plates 21 to 26, but the incline 81 allows the pin to enter groove 80 so that the tip 90 can engage the top sheet at area 17 through the slots 27, and slide it out of mouth 29, collating it with the other sheets to carry the assembly on the conveyor 37 at which place groove 80 ends in the incline 84 to cause the hook member 78 to assume position 78' and lift the carrying member 33 to position 33' in which position it remains while travelling around both sprockets until the pin 79 is again deposited on the top of cam 14. The action of each member of one group may be alternated by the action of the corresponding member of the other group which is arranged in the same way as can be understood, so that each complete revolution of the chain assembly produces two assemblies of collated patterns.

When the collated assembly emerges from between the conveyors 37 and 38, the variously shaped points of the patterns continue to travel on conveyor 37 until they hit roller 98 (Fig. 8), which deflects them upwards and has preferably a circumferential speed superior to the speed of the conveyor. The forward ends are further deflected by contact with roller 99 and with the inside surface of the exit gate 100, supported by the shaft members 102 rotatably supported by the frame 1.

The shaft 104 is also rotatable in the frame and supports the slide wing 105, the lower portion of which has a roughly cylindrical shape to complete the cylinder to be formed by the patterns. 75

This wing has slots 106 to allow discs to reach through it. The shaft 104 has an arm 107 supporting cam followers 108 to cooperate with the cam 109 on the cam shaft 110 (Figs. 7 and 8). 5 This cam shaft is arranged to be driven by the sprocket 111 from the shaft 3 in a ratio to make two complete revolutions for each complete revolution of the chains 9. The shaft member 104 rotatably supports a pair of plates 114 forming the roller wing supporting a cam follower to cooperate with cam 115 and shafts 116, 117, 118 on which discs 119 are supported in spaced apart relation to fit in the slots 106 of the slide wing 105. These shafts are also driven to have the same circumferential speed as 98 and 99. One shaft member 102 is linked to a cam follower cooperating with cam 123 on shaft 110. Behind the exit member 100, the shafts having rollers 124 and 125 are arranged and may be driven in opposite directions at a preferably slower speed and behind them the rollers 126 and 127 may be driven at speeds identical to those of 124 and 125. 10 The discs 119 on shafts 116, 117, and 118 further deflect the forward ends of the patterns and in cooperation with the tops of the slide wing 105, lead them back to form a complete cylinder or roll. As the roll continues to rotate and further layers of pattern sheets are added, its outer diameter increases. To allow for this increase, the cams 109 and 115 move the slide wing 105, and the roller wing 114 to a position indicated by broken lines 105', which is reached when the rolling-up is completed. Cam 109 then starts to move the slide wing forward to position 105'' while cam 123 moves the exit gate 100 to the position 100' shown in broken lines. Both movements add to brake the upper and right portion of the roll and to put pressure on it, which, together with the rotating rollers 98 and 99 and the conveyor 37, causes the roll to bulge at the place formerly occupied by the exit gate 100, to be pressed against the rollers 124 and 125 which start to pull the roll between them, transforming it to a fold. In order to allow the air within the roller more time to escape, the rollers are preferably not quite adjacent. The fold is then completed by the adjacent rollers 126 and 127 which deliver the fold to the table 42. 15 20 25 30 35 40 45 50 55 60

A modification of this folding mechanism is shown in Fig. 9. In sequence to the rollers 98 and 99, the shafts 130 and 131 are arranged to support discs 119 in spaced apart relation. The exit wing 132 has slots to allow these discs to pass and is secured to the shaft segment 133 rotatably supported by the frame at 134 and movable by the cam 123 to assume the position 123' when the rolling-up is completed, allowing the roll to be pressed against the discs on 131 which flatten the roll in cooperation with the discs on 130 and transport it to be engaged by the rolls 126 and 127, finishing the fold. 65

I claim:

In a collating machine wherein a number of sheets are to be collated, superimposed plates arranged in spaced apart relation to support said sheets, said plates having their front ends staggered in one direction, means to support said sheets to allow a mouth transverse to said direction to remain between each pair of adjacent plates so arranged that sheets from all plates can be moved in said direction through these transverse mouths, said sheets being disposed on their respective plates rearward of the front edge thereof; groups of carrying members at least one group for each plate, moving means to move in said direction, and support said carrying mem-

bers in groups, each carrying member of one group having a definite position within its group and all groups begin similar, each carrying member of one group moving along a path to pass over an area of contact of each said carrying member with one of said sheets, longitudinal slots along said paths arranged in said plates over each said contact area to extend in said direction of movement to said transverse mouths, the slots in each plate being out of line with those in every other plate means arranged along said path to cause an additional motion of each carrying member to contact a sheet on said contact area through said longitudinal slots, spring means on said moving means to urge said carrying members to contact said sheets through said slots and to apply pressure on them to convey them through

said transverse mouths to assemble them, said definite relation between said carrying members of each group being similar to the relation of said contact areas on the plates.

AUGUST G. LUISADA.
